UNITED STATES PATENT OFFICE.

TALBOT C. DEXTER, OF DES MOINES, IOWA, ASSIGNOR OF THREE-FOURTHS
TO W. E. ANDREWS, OF SAME PLACE.

PAPER-FOLDING ATTACHMENT FOR PRINTING-PRESSES.

SPECIFICATION forming part of Letters Patent No. 247,178, dated September 20, 1881.

Application filed November 9, 1880. (No model.)

To all whom it may concern:

Be it known that I, TALBOT C. DEXTER, of Des Moines, in the county of Polk and State of Iowa, have invented an Improved Paper-Folding Machine, of which the following is a specification.

My invention contemplates folding printed sheets successively and as rapidly and regularly as they are delivered from the forms of a press by means of folding mechanism attached to the press and automatically operated in concert with the printing mechanism by the driving-power of the press.

It consists, first, in combining a folding-blade direct with the fly of the press, to be automatically operated by the fly for the purpose of doubling printed sheets and placing them between parallel folding-rollers. Heretofore a bar or feeder has been connected with a fly by means of an intermediate frame, to be automatically operated through the medium of the frame and the fly; but by connecting a folding-blade direct with the bar of a fly by means of links I dispense with an auxiliary frame and relieve the fly from a burdensome weight, and thereby greatly facilitate the movements of the fly and the folding-blade carried thereby in accomplishing the regular delivery and folding of the printed sheets; second, in combining my paper-moving and sheet-doubling mechanism with a fly-board, table, or machine having a pair of folding-rollers adapted to receive a sheet when doubled in the center; third, in combining an adjustable bar, adjustable feeders, and adjustable sheet-stopping gages with folding-rollers, to facilitate the adjustment of the complete machine as required to fold sheets of various sizes at various times; fourth, in forming journals on the sides of a follower in a paper-packing box, and combining it with a box in such a manner that it will have a vibrating motion, and also a rectilinear motion, to facilitate the moving and packing of the folded papers as they drop successively from the folding mechanism; fifth, in arranging and combining the sheet-doubling device carried on the fly of the press, folding-rollers, sheet-carrying tapes, folding-blades, sheet-stopping and sheet supporting and governing

devices, driving mechanism, and a packing device, all as hereinafter fully set forth.

Figure 1 of my accompanying drawings is a sectional view, showing my folding-blade attached to the fly of a press immediately over a pair of rollers mounted in a fly-board or suitable table. Fig. 2 is a top view of my folding mechanism located under the fly-board or table underneath the fly. The top and parts of the operating devices are broken away to disclose the relative positions and functions of all the combined elements. Fig. 3 is a side view taken from the right side of Fig. 2. Fig. 4 is an end view taken from the lower side of Fig. 2. Fig. 5 is an end view taken from the top side of Fig. 2. Fig. 6 is an enlarged detail view of one of my folding-blades and of one of the cams that operate my series of blades in succession, as required to make successive folds in a sheet.

A in Fig. 1 represents the frame of a printing-press; B, the fly, and C a fly-board or table.

d is a folding-blade, detachably connected with the center bar of the fly B by means of links *d'*, or in any suitable way that will allow the blade to drop or move downward when the fly swings downward, and to fold close to and within the fly when the fly assumes a vertical position.

d'' represents a spring connected with the rear end of the suspended folding-blade *d* and the floor or some fixed object by means of a flexible strap, or in any suitable way, for the purpose of aiding in folding and unfolding the blade *d* relative to the fly B, with which it is detachably connected.

In place of the spring *d''*, a cam may be attached to the frame of a press in such a position relative to the fly and the lower end of the folding-blade *d* that it will engage and operate the said blade.

C C C in Fig. 2, representing the fly-boards and cover of the folding mechanism, rest upon the top of a rectangular frame, *b b b*, which is preferably formed in sections, of cast metal, 95 and bolted together.

Nos. 1 and 2 are a pair of rollers, mounted in parallel position near the surface of the fly-

board or cover C, and in such position that they can be placed immediately under the center of the fly and the folding-blade d carried thereby. An opening in the said cover extending 5 the length of the folding-blade allows said blade when it descends to double a printed sheet carried by the fly and to place the doubled center of the sheet between the rollers 1 and 2, as required, to pass the sheet between 10 the rollers, and thereby complete the first fold in the sheet.

c is the main driving-shaft of my folding mechanism. It is mounted in suitable bearings formed in or attached to the frame b b, 15 and has a chain-pulley, c', on its end outside of the frame.

c'' is a chain-belt on the chain-pulley c', that extends to a chain-pulley connected with the driving mechanism of the press, as required, 20 to transmit power and motion from the press to the driving-shaft c of the folding mechanism.

e is a minor driving-shaft, mounted in the frame in a right-angled position relative to the 25 shaft c, with which it is connected by means of bevel-gearing, as shown.

f is a second minor shaft, mounted in the top portion and right side of the frame to extend in parallel position with the shaft e and 30 entirely across the frame.

f'' represents a chain-belt, that extends over two chain-pulleys that are respectively fixed to the parallel shafts e and f. By thus connecting the two shafts power and motion is 35 transmitted to the shaft f.

f''' is a chain-belt connecting the shaft f with the shaft of the roller No. 1 by means of chain-pulleys on the ends of said shafts, as required, 40 to transmit power and motion to rotate the said roller. Nos. 1 and 2 rollers are connected by means of gear-wheels on the ends of their axles, as shown in Fig. 4, and as required to revolve toward each other to move the doubled sheets through downward between the rollers

45 to complete the first fold and to deliver it upon a series of carrying-tapes, g, that surround the roller No. 1, and, passing underneath the roller No. 2, are connected with and operated by a corresponding series of pulleys, g', fixed on 50 the shaft f, as required, to place the folded sheet in position to have a second fold made at right angles to the first fold. A plate, xx, (shown in Fig. 2,) fixed to the frame, extends partly under along the roller No. 2, to serve as 55 a guard to prevent sheets from wrapping around said roller.

Nos. 3 and 4 is a second pair of rollers, mounted in adjustable bearings on the frame in a right-angled and central position relative to 60 the rollers Nos. 1 and 2, and in a plane below the tapes g.

h is a folding-blade of elbow shape, as shown in Fig. 6, the horizontal portion of which extends immediately over the rollers Nos. 3 and 65 4, as required, to double the folded sheet a second time and to start it downward between the

said rollers. The rear end of the horizontal portion thereof has an upward bend, adapting the complete blade to be operated over and around the bearings and gearing at the ends 70 of the contiguous and parallel folding-rollers. Said upward bend is in the form of a double elbow, 2 2, as plainly shown in Fig. 6.

h' is an adjustable guide and bearer, through which the vertical portion of the blade h extends downward. A slot in the frame b allows a screw-shank on the end of the bearer h' to extend outward and to form a bearing for it in which it can be adjusted laterally, as required, to follow the adjustment of the rollers, which 80 is necessary at times to accommodate them to the size and center of the double sheet that is to be folded a second time.

h'' is a thumb-nut, by means of which the bearer h' is clamped fast to the frame in the 85 slot h''. (Shown in Fig. 3.)

h''' is an anti-friction roller on the lower end of the elbow-shaped blade, that engages an adjustable crescent-shaped cam, i, that is fixed on the shaft e in such a position relative to the 90 rollers 3 and 4 that the horizontal portion of the blade will rise and fall between the said rollers at every revolution of the shaft e and cam i, by means of which the blade is actuated to double the sheet a second time and place it 95 between the rollers, to be thereby moved downward upon a second series of carrying-tapes, k, that surround the roller No. 3 and extend laterally under the roller No. 4 to a third pair of rollers, where a third fold is made in the 100 sheet.

Nos. 5 and 6 are the third pair of rollers, mounted in adjustable bearings in a plane below the rollers 3 and 4, but in parallel position therewith. The bearings of these two pairs of 105 rollers, 3 4 and 5 6, are detachably and adjustably connected with the frame by means of set-screws that extend through slots in the frame or in any suitable way. Power and motion is communicated to the rollers 4 and 6 from the 110 driving-shaft c by means of chain-pulleys and a chain, as clearly shown in Fig. 5.

A second folding device, h h' h'' h''' h''', (adapted to be operated perpendicularly over and around the bearings and gearing at the 115 ends of a pair of horizontal folding-rollers and between two series of paper-carrying tapes moving at right angles to each other,) is connected with the shaft e, having a second cam, i, and the rollers 5 and 6, as required, to double 120 the sheet a third time and start it downward between the rollers 5 6 to be carried laterally to a fourth pair of rollers by means of the tapes k, that pass over the roller 5 and under the roller 6 to rollers 7 and 8, mounted by 125 means of brackets l at the end of the frame b b. Each one of these elbow-shaped folding-blades h has an upward bend or arch in its angle, and by varying the heights of those arches both blades are adapted to work around the driving-gear on the ends of the rollers, and also around the tape-supporting device, that pre- 130

vents the first and upper series of sheet-carrying tapes from sagging and interfering with the advance of the sheet on a second and lower series of tapes.

5 No. 7 is a grooved anti-friction roller, mounted in fixed bearings formed on or attached to the brackets *l*, and the tapes *k* run in its grooves and are guided thereby.

No. 8 is an anti-friction roller mounted in 10 adjustable bearers *l'*, by means of which the roller is readily adjusted relative to the rollers 3, 4, 5, 6, and 7, as required, to loosen or tighten the series of continuous tapes *k*, connected with said series of rollers.

15 Nos. 9 and 10 are the fourth pair of rollers, through which the sheet is passed to produce a fourth fold in the sheet. They are mounted in adjustable bearings connected with the frame, and in a right-angled position relative 20 to the rollers 5 and 6. They are connected by gear-wheels on their ends, and motion is imparted thereto by means of a chain and chain-pulleys from the shaft *e*, as shown in Figs. 2 and 3. A folding-blade, *h*, is combined and operated with the rollers 9 and 10 by means of a bracket, *m*, adjustably fixed to the top portion 25 of the frame, in which bracket slots or bearings are formed, through which the vertical portion of the elbow-shaped blade *h* extends upward, and also by means of a hinged lever, *m'*, (shown 30 in Fig. 4,) that has a branch, *m''*, extending to a cam, *i*, on the end of the shaft *e*. This lever *m'* is hinged to the frame by means of a block or bracket, *n*, and is flexibly connected with

35 the elbow-shaped folding-blade, that rises and falls in its bearings in the bracket *m*, and has an anti-friction roller at the lower end of its branch, where it is connected with the cam *i* and shaft *e*, from which shaft motion is imparted at each revolution of said shaft to vibrate the lever and actuate the folding-blade, 40 as required, to make a fourth fold in the sheet and start it downward between the rollers 9 and 10, to be disposed of in a delivery-box.

45 *r* (shown at the bottom of Fig. 2) is a bar adjustably connected with the frame by means of brackets *r'*.

r'' are fenders fixed to the bar *r* at their ends to extend horizontally toward and partly over 50 the roller No. 6, for the purpose of receiving the folded sheet as it is carried over the rollers 5 and 6 by means of the series of tapes *k*, as required, to bring its center immediately under the folding-blade *h*, that will double it again and start it downward between the said 55 rollers.

s (shown in Figs. 2 and 4) is a bar extending across the frame *b*, to which its ends are fixed, in such position relative to the series of tapes 60 *g* that a series of fenders, *s'*, extending downward from the bar will arrest the further movement of the sheet carried on said tapes.

t t represent a series of fenders adjustably connected with the bar *r* (shown in Fig. 2) in 65 such a manner that they can be readily adjusted relative to the rollers Nos. 34 and 56, as required,

to stop the movement of the sheet carried by the series of tapes *k* at the proper point to allow the same to be doubled in its center by the folding-blade *h* and started downward between 70 the rollers 5 and 6.

w (shown in Figs. 2 and 3) is a rod connected with the adjustable bearings of the rollers 3 and 4 in such a manner that it will extend laterally from the rollers and through the 75 frame to receive a thumb-nut on its end, by means of which it can be drawn out and in to adjust the said bearings and rollers. Anti-friction rollers placed loosely on this rod *w* serve to hold up the tapes *g*, as required, to prevent 80 them from sagging, and allowing the sheet carried thereby from coming into contact with the blade *h*, that, by means of the upward bend or arch in its angle, is adapted to work around the rod *w*, and co-operates with the rollers 85 5 and 6.

D (shown in Fig. 4) represents a delivery-box in the form of a trough placed immediately under the rollers 9 and 10 and at right angles thereto. One of the sides of this elongated box may be adjustably connected, so that it can be moved laterally relative to the other fixed side, as required, to correspond with the size of the folded sheets dropped into it from between the rollers 9 and 10, where the 95 last fold was completed.

G is a loose block that slides in the box *D*. Its rear end is inclined, and the folded papers that accumulate in the box rest against the 100 inclined end of the block.

H is a vibrating follower that is pivoted in the box by means of journals extending outward therefrom and through horizontal slots *a* formed in the sides.

I is a jointed lever, flexibly connected with 105 the follower *H*, and pivoted to the frame of the machine in such a position relative to the shaft *e* that a curved bar, *J*, fixed to the short arm of the pivoted and jointed lever *I* will engage a cam, *J'*, fixed on the shaft *e*. Every 110 revolution of said shaft *e* will cause the cam *J'* to actuate the jointed lever and vibrating follower *H*, connected therewith, as required, to place the folded papers consecutively into an inclined position against the inclined end of the 115 block *G*, which holds up the column of papers packed against it and recedes as the number of papers increases.

a' is a spring fixed to the base of the box *D*, and also to the lever *I*, in such position that 120 the spring will draw back the follower *J* and reverse its inclination when the pressure that moves the follower forward is relaxed.

I am aware inclined followers or plungers have been operated in a packing-box; but my 125 manner of imparting a vibrating motion to the follower to facilitate the moving and packing of the folded sheets is novel and advantageous.

From the foregoing detailed description of the construction and function of each and every part of my invention their unitary and concerted actions are obvious, and the practical 130

operation and utility of the complete machine clearly demonstrated.

I claim as my invention—

1. The sheet-doubling device consisting of a folding blade, *d*, links *d'*, and a spring, *d''*, in combination with the fly of a printing-press, substantially as shown and described, to operate in the manner set forth.

2. The paper moving and doubling mechanism consisting of the fly *B*, the folding-blade *d*, the links *d'*, and the spring *d''*, in combination with a pair of folding-rollers mounted in a fly board, stand, or frame, and adapted to receive the sheet delivered by the fly and to complete the fold started by the folding-blade, substantially as shown and described.

3. The combination of the adjustable folding-rollers Nos. 5 and 6, the adjustable bar *r*, the adjustable fenders *r''*, and the adjustable sheet-stopping gages *t*, substantially as shown and described, for the purposes specified.

4. The packing-box *D*, having slots *a* in its sides, the follower *H*, having journals extending through said slots *a*, the jointed lever *I J*, the spring *a'*, and the cam *J'* on the shaft *e*, arranged and combined substantially as shown

and described, to operate in the manner set forth, for the purposes specified.

5. The paper folding and packing attachment for printing-presses, consisting of the following groups of operative devices and sub-combinations, to wit: the sheet-doubling device *d d' d''*, carried by the fly of the press; the folding-rollers Nos. 1 and 2; the series of sheet-carrying tapes *g* and operative pulleys *g'* on the shaft *f*; and sheet-stopping device *s s'*; the adjustable rollers Nos. 3 and 4 and an adjustable folding-blade, *h*; the rollers Nos. 5 and 6, 7 and 8, carrying-tapes *k*, folding-blade *h*, and tape-supporting device *w x*; the sheet supporting and governing devices *r r' r'' t t*; the rollers Nos. 9 and 10 and the pivoted lever *m m'*, carrying a folding-blade; the packing-box *D a*, follower *H*, jointed lever *I J*, spring *a'*, and cam *J*, and the driving-shafts *c e*, all arranged and combined relative to each other and a printing-press substantially as shown and described, to operate in concert as set forth.
